A. Fuller,
Cock,
No 21,332 Patented Aug. 31, 1858.

UNITED STATES PATENT OFFICE.

ALBERT FULLER, OF CINCINNATI, OHIO.

STEAM-COCK.

Specification of Letters Patent No. 21,332, dated August 31, 1858.

To all whom it may concern:

Be it known that I, ALBERT FULLER, of Cincinnati, in the county of Hamilton and State of Ohio, have invented a new and 5 Improved Steam-Cock; and I do hereby declare that the following is a full, clear, and exact description of the same, reference being had to the annexed drawing, making a part of this specification, said drawing being a longitudinal central section of my invention.

This invention consists in having a plug of rubber or other suitable elastic material placed on the valve stem and fitted between 15 a metallic shield on one side and a metallic cap on the other, the cap having a nut bearing against it, and the parts arranged as hereinafter fully shown and described, whereby due provision is made to compensate for the wearing of the plug, and the 20 casualty of the forcing of the plug through the valve seat by the pressure of the steam effectually guarded against.

To enable those skilled in the art to fully 25 understand and construct my invention I will proceed to describe it.

A, represents the tube of the cock which may be formed of two parts *a*, *b*, connected by screw threads *a'*, the end of part *a*, forming 30 a valve seat *a**, and being of annular concave form.

B, is a tube which joins tube A, at right angles and has an arbor C, fitted within it, said arbor being retained in proper position 35 by a shoulder *c*, and cap *d*, the latter being screwed on the end of tube B, as shown clearly in the drawing.

The lower end of the arbor C, has an arm *e*, projecting eccentrically from it, and this 40 arm fits into the eye *f*, of a valve stem D. On this stem D, a plug E, is placed, said plug being of rubber or other suitable elastic material and of such size that when not subjected to pressure, it will be somewhat larger 45 in diameter than the internal diameter of the part *a*.

The plug E, is placed between a metallic shield *g*, and a cap *h*—the shield *g*, is of sufficient diameter to fit snugly the inner

portion of the seat *a**, if the shield is forced 50 against it. The face of the shield *g*, is concave to form a sort of socket to receive the plug and the cap *h*, is a metal shell which fits over the greater portion of the steam side of the plug E. The outer end of the 55 stem D, has a screw thread formed on it to receive a nut F.

The interior of the part *b*, is larger in diameter than the part *a*, as shown clearly in the drawing so as to allow the plug E, 60 to be of a diameter greater than *a*, and receive the plug E, and the upper end of the arbor C, is provided with a handle G.

From the above description it will be seen that by turning the arbor C, the plug E, will 65 be drawn snugly to and moved from its seat *a**, and it will also be seen that the shield *g*, in bearing against the inner part of the seat *a**, will prevent the plug from being forced through the seat *a**. The shield also prevents the abrasion of the plug, and by screwing up the nut E, the plug will be expanded 70 so that all wear may be readily compensated for.

I am aware that elastic plugs or valves 75 have been previously used for steam cocks and that nuts have been arranged or applied to them for the purpose of expanding them, but, I am not aware that any have been arranged like the one herein described with a 80 shield and cap for the purpose of not only expanding the plug when necessary, but also preventing abrasion and the plug from being forced through the valve seat by the pressure of the steam. I therefore do not 85 claim broadly the elastic plug E, but,

I claim as new and desire to secure by Letters Patent,

Placing the elastic plug E, on the valve stem D, between the metallic shield *g*, and cap *h*, the parts being arranged relatively 90 with the valve seat *a**, substantially as and for the purpose set forth.

ALBERT FULLER.
